ELECTRODYNAMIC LOUDSPEAKER

Adolf Poggendorff, Berlin-Weissensee, Germany,
assignor to Gesellschaft für Drahtlose Tele-
graphie m. b. H., Berlin, Germany, a corpora-
tion of Germany

Application April 13, 1932, Serial No. 604,939
In Germany August 13, 1931

4 Claims. (Cl. 179—115.5)

The invention relates to acoustic apparatus. More particularly, it relates to acoustic apparatus of the electrodynamic or moving coil type.

In the operation of electrodynamic loudspeakers it has been found that occasionally the supply leads start to oscillate whenever they happen to become excited at their natural period. As a result of such vibrations the wires may break off especially at the points where they are attached 10 to the diaphragm or at the terminals in the casing. The comparatively stout and therefore less yielding (more brittle) loudspeaker supply leads whose driving element consists of a single conductor or whose diaphragm is itself designed 15 to act as the current supply element, are particularly sensitive. The feed leads in this case must be made quite rugged since occasionally they have to carry currents up to 120 amps.

In an attempt to obviate this drawback, it has 20 previously been suggested in the art to round off the edges of the terminals, but this plan gives the desired results only in a few instances.

According to the present invention the above difficulties are overcome by artificially damping 25 the supply leads. The damping is effected by the provision of supplementary masses (lead cables) or by the action of additional damping elements upon the conductors. The additional damping material may be felt or rubber, or some 30 similar substance insuring high damping or deadening of vibrations, though the same effect might also be insured electrically. Such supplementary masses cause a shift in the natural period into a region where the exciting force is low. Since in 35 the movement of the conductors such supplementary masses are subjected to deformation, this means the production of energy consuming work; in other words, damping is thereby produced.

According to another object of the invention 40 it will be found of advantage in the above scheme to provide some yielding material like rubber to be interposed at the point where the unsupported conductor passes over into the binding post so that the clamping means will be able to yield whenever subjected to stress caused by vibrations.

The figures show embodiments of the basic idea of the invention, Fig. 1 showing the ways and means to feed the currents to the voice coil of a standard plunger type coil loudspeaker. Fig. 50 2 shows a further embodiment of the basic idea of the invention.

In Fig. 1, the connection from the output of the amplifier (not shown) is effected at the terminal board or plate 1 from which the leads 2 and 3 are brought to the voice coil 4. The leads are each

enveloped with a sheath or cable 5' of lead or rubber in which mineral powder has been incorporated in order to raise the damping. This causes an increase in the mass which, in turn, exercises an influence upon the damping of the 5 natural period.

In Fig. 2 there is illustrated schematically a loudspeaker of the dynamic type in which the current conducting element occasioning the mechanical drive comprises a single conductor. In 10 such arrangements which are especially suited for large power loudspeakers, it is necessary to provide rather stout supply leads to meet the demands of the electrical load. But, on the other hand, the supply leads should not be chosen too 15 heavy since they would otherwise tend to unduly increase the inert mass partaking of the oscillations, or else they might impair the chances for free vibrations of the system because of their stiffness. Such supply leads possessing relative- 20 ly high brittleness, as pointed out before, are very sensitive to an excitation of their mechanical natural period so that damping means must be provided.

Fig. 2 shows an arrangement of this kind. The 25 conductor 5 is clamped together with the terminal board 6 with rubber layers 7 being suitably interposed. The clamping is preferably made so firm that the damping effect of the rubber gets a chance to make itself felt. Rubber 30 compounded with a mineral powder is most suitable since such rubber evidences very high damping properties. The conductors 5, which are brought unsupported from the terminals 6, are further supported between felt pads or bodies 8. 35 Felt has different damping properties than rubber so that the conductors are embedded or interposed between materials having dissimilar effects. Other materials possessing a similar action may be employed in lieu of rubber or felt. 40

What I claim is:

1. An electrodynamic loudspeaker having a vibratile system including a voice coil, a diaphragm connected with said voice coil, leads for supplying energy to said voice coil, means on said leads for subjecting said vibratile system to mechanical damping, said means comprising damping materials possessing dissimilar damping properties arranged one behind the other in the 45 direction of the leads.

2. An electrodynamic loudspeaker having a vibratile system including a voice coil, a diaphragm connected with said voice coil, energy supply leads for said voice coil, a terminal board and felt placed between said supply leads as they 50 55

are brought away from said terminal boards whereby said felt applies a mechanical damping to said vibratile system.

3. Acoustic apparatus of an electrodynamic type including a vibratile voice coil, voice coil leads extending to fixed points and metallic sheaths of substantial mass surrounding said voice coil leads to damp the vibrations thereof.

4. Electrodynamic acoustic apparatus compris-

ing a vibratile system including a voice coil, voice coil leads extending to fixed points, said voice coil leads having natural periods of vibration and damping members in the form of lead cables surrounding said voice coil leads for effectively damping the vibrations of said leads at the frequencies of their natural periods.

ADOLF POGGENDORFF.
